UNITED STATES PATENT OFFICE.

JOHN J. FLEMING, OF VINELAND, NEW JERSEY.

MOLD FOR SASH-WEIGHT CORES.

Application filed September 29, 1925. Serial No. 59,251.

To all whom it may concern:

Be it known that I, JOHN J. FLEMING, a citizen of the United States, residing at Vineland, in the county of Vineland and State of New Jersey, have invented certain new and useful Improvements in Molds for Sash-Weight Cores, of which the following is a specification.

My invention relates to molds for sash weight cores which are used in molding the cord-attaching end of sash weights.

The chief objection, common to the numerous methods of making sash weight cores, is that considerable time is required for making the cores. This makes them a costly item in the manufacture of sash weights. Another objection is that the apparatus, used for making the cores on a large scale, is bulky and of many parts which makes it complicated and unhandy to use. A further objection common to many methods is that the weight indicating numbers are not molded on a conspicuous part of the sash weight which makes it difficult to find a proper weight among a group of different weights.

The objects of my invention are to provide a mold for making sash weight cores, of comparatively simple and compact construction, which may be easily handled to quickly produce large quantities of cores at low cost; and to provide a mold which will produce a core of such character, that it will form a cord-attaching end on a sash weight having the weight indicating numbers in a conspicuous place.

These objects, and other advantageous ends which will be described hereinafter, I attain in the following manner, reference being had to the accompanying drawings in which—

Figure 1 is a plan view of a mold made in accordance with my invention,

Figure 2 a central section through the mold shown in Figure 1 showing it filled with sand, some of the parts being shown in full,

Figure 3 a view similar to Figure 2 showing some of the parts in another position,

Figure 4 a section on line 4—4 of Figure 1,

Figure 5 a section on line 5—5 of Figure 1 showing some of the parts broken away,

Figure 6 a perspective view of elements which form a part of my invention, 55

Figure 7 a view similar to Figure 2 showing a modified form, and

Figure 8 a perspective view of a core.

Referring to the drawings, 1 indicates a mold casing having a plurality of mold cavities 2 of similar shape. Each cavity has a cylindrical part 3 opening at the upper side of the mold casing and a slotted part 4 communicating with the cylindrical part and opening at the lower side of the mold 65 casing. Bar passages 5 are provided through the walls of the cavities for slidably receiving a marking bar 6 and a plain bar 7 which pass through the cylindrical parts of the mold cavities. Marking bar 6 70 is provided with symbols 8, corresponding to the weight of the sash weight to be molded by the core, which are disposed in each cavity. Plain bar 7 passes through the cavities alongside of the marking bar 75 to keep the same in position. A suitable locking member 9 in the form of a pin passes through the casing and through the bars to lock them to the casing. For purpose of simplifying the machining of bar 80 passages 5, casing 1 is preferably made in lengthwise half sections so that half of each passage 5 may be readily machined in one section and the other half in the other section. 85

In Figure 7, I have shown a form in which two marking bars 6^a pass through the cavities 2^a and passages 5^a with their symbols 8^a disposed in the cavities so that the cores produced will have two symbol- 90 impressions thereon for molding two weight-markings on the attaching end of a sash weight. When this form is used the plain bar 7^a is placed between the marking bars and locked with them to the casing by the pin 9^a. In all other respects the mold is similar to the mold shown in Figures 1 to 6 and I have therefore given corresponding parts similar reference characters with the exponent "a."

In making the cores with my improved mold, the bar 6 and plain bar 7 are slid into the casing to pass through the cavities and locked thereto by the pin 9. The mold cavities are then filled and rammed with sand, after which pin 9 is removed and 105

plain bar 7 slid out of the casing. Marking bar 6 is then shifted sidewise away from the symbol impressions 10 left in the sand and slid out of the casing. When the form 5 shown in Figure 7 is used, the other marking bar 6^a is likewise shifted sidewise away from the impressions and slid out of the casing. The casing is then turned up-side down and tapped slightly until the cores 10 fall out of the cavities. The core produced by each cavity is as shown in Figure 8. These cores are then used for plugging the end of a sash weight mold and form the cord-attaching end on a sash weight. The 15 opening 11 in the core, having the symbol impressions 10 in its sides, was formed by marking bar 6 and plain bar 7. This opening forms the flat part on the end of the sash weight. The part 12 of the core, 20 which was formed by the slotted part 4 of the mold cavity, forms the cord-attaching opening through the flat part on the end of the sash weight. The symbol impressions 10, which are preferably numbers, 25 form the number on the side walls of the flat part which may be easily seen at a glance.

It is thus seen that constructing a core mold as above set forth, produces a comparatively simple mold which may be conveniently handled to quickly produce large quantities of sash weight cores, and that the cores produced form a cord-attaching end on a sash weight which has the weight 35 indicating numbers in a conspicuous place.

While I have described my invention as taking a particular form, it will be understood that the various parts may be changed without departing from the spirit thereof, 40 and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A mold for making sash weight cores including a casing having a mold cavity; a 45 bar slidably mounted in the casing passing through the cavity and having a marking

thereon disposed in the cavity, and a second bar slidably mounted in the casing adjacent the first mentioned bar.

2. A mold for making sash weight cores 55 including a casing having a plurality of mold cavities; a bar slidably mounted in the casing and passing through the cavities and having a marking thereon disposed in each cavity, and a second bar slidably mounted 60 in the casing adjacent the marking bar.

3. A mold for making sash weight cores including a casing having a mold cavity; a bar slidably mounted in the casing, passing 65 through the cavity, and having a marking thereon disposed in the cavity; a second bar slidably mounted adjacent the first mentioned bar, and means for locking the bars to the casing.

4. A mold for making sash weight cores 70 including a casing having a cylindrical part opening at one side and a slotted part, communicating with the interior of the cylindrical part, opening at the other side; a bar slidably mounted in the casing passing through and having a marking disposed in the cylindrical part, and a second bar 75 slidably mounted in the casing adjacent the first mentioned bar.

5. A mold including a sectional casing 80 having a plurality of mold cavities and aligned bar passages through the walls of the cavities; a marking bar slidably mounted in the passages and having a symbol disposed in each cavity; a second bar slidably mounted in the passages for holding the marking bar in position, and means for locking the bars to the casing.

6. A mold including a sectional casing 85 having a plurality of mold cavities and aligned bar passages through the walls of the cavities; a marking bar slidably mounted in the passages and having a symbol disposed in each cavity; a second bar slidably mounted in the passages for holding the marking bar in position, and a pin passing 90 through the casing and the bars for locking them to the casing.

In testimony whereof I have signed my name to this specification.

JOHN J. FLEMING.
